UNITED STATES PATENT OFFICE.

ISIDORE HIRSCH, OF NEW YORK, N. Y.

MEANS FOR RENOVATING PRINTER'S TYPE.

Application filed October 14, 1926. Serial No. 141,458.

My present invention, like that set forth in my concurrent application Serial No. 44,499, filed July 18th, 1925, is designed to afford adequate means whereby printer's type may be quickly and conveniently manipulated for cleansing purposes without disturbing the relative arrangement thereof as distributed to the box compartments of a compositor's ordinary case in which the separate letters of a font of type are segregated in a manner well known in the art, and the invention consisting primarily and essentially in the specific combination, construction and arrangement of component parts and appurte-
nances of the rotatable type-holding and washing apparatus described and claimed, whereby these and other advantageous results are attained, the distinctive feature in the present case being the unitary construc-
tion of wash-tray corresponding in size, shape, and compartments to a compositor's type case, and provided with a detachable cover and trunnion means admitting of rotation of both wash-tray and cover.

In the accompanying drawings I illustrate a practical embodiment of the essential features of my invention in type cleaning apparatus of the character designated, comprising a tray formed with a series of intersticed or reticulated pockets or compartments corresponding in size, number, and relative arrangement to the individual type-box compartments of the compositor's case in conjunction with which the tray is to be used, together with reticulated means for retaining the types therein, and for rotating the same, for the purpose set forth, although I do not restrict myself to the identical form and construction of component parts shown by way of exemplification herein, since changes may be made in minor details, and equivalent mechanical expedients resorted to, with like results, and without departing from the spirit and intent of my invention in this respect.

Fig. 1, represents a top view of the open face of a unitary type wash-tray;

Fig. 2, is a side elevation, partly in section on plane of line 2-2, Fig. 1; representing the wash-tray shown therein as superposed on the type setter case for which it is provided;

Fig. 3, is an end elevation of the wash-tray shown in Fig. 1;

Fig. 4, is a view of the tray cover;

Fig. 5, is an edge elevation thereof;

Fig. 6, is a view of one of the cover bolt rods.

The wash-tray T, is of a length and width corresponding in size and shape to the compositor's type case for which it is especially provided, and is formed with a series of pockets or type receptacles t, t, the entrances of which (as indicated particularly in Fig. 1, of the drawings) coincide in size and shape with the type-box compartments c, of the compositor's type case C, it being understood, of course, that each special form and arrangement of compositor's type case C, requires a corresponding modification in the construction and arrangement of my integral unitary wash-tray T.

The type receptacles or pockets t, in the wash-tray T, are deeper and of greater internal area and capacity than the corresponding type box-compartments c, in the compositor's case C, so as to afford ample room for freedom of movement of the types in the pockets during the rotative cleansing operation; and the side and end walls of said pockets are reticulated to admit of the passage of a cleansing liquid.

In use, the wash-tray T, is superposed on the compositor's type case C, as indicated in Fig. 2, and when thus superposed and clamped together by suitable means, this temporary combination of wash-tray T, and type case C, is reversed, resulting in the transfer of the types from the box-compartments c, in the compositor's case C, to the corresponding and coincident type pockets t, in the wash-tray T, after which the said case C, is disconnected and removed from the wash-tray T.

After the disconnection and removal of the compositor's type case C, from the wash-tray T, as above stated, a reticulated cover A, is positioned over the otherwise open face of the wash-tray T, being secured thereto by longitudinal bolt rods b, b, which are inserted in and through eye-knuckles t', t', provided for the purpose on the sides of the wash-tray T, and in and through like, but intervening eye-knuckles a, a, on the longitudinal sides of the screen or cover A, thereby confining the types in the pockets t, of the wash-tray T.

Trunnions t², t², are provided on the ends of the wash-tray T, for the purpose of rotatably mounting it and its reticulated cover A, upon and in such relation to a tank containing a suitable cleansing liquid that the

rotation of the covered wash-tray therein by suitable mechanical expedient insures the immersion, agitation and cleansing of the types in the pockets t , of the wash-tray T .

5 At the conclusion of the washing operation, the cover A , is removed from the wash-tray T , and the compositor's type case C , is again superposed thereon and clamped thereto, when the reversal of the two insures 10 the return of the washed types to their respective box-compartments in the compositor's type case C . Hence, the disconnection and removal of the inverted wash-tray T , from the compositor's type case then leaves 15 the cleaned type practically as good as new, in its original relative character arrangement in said case.

Thus by the use of my type washing apparatus as herein set forth, not only the 20 faces, but also other portions of the individual types are cleansed and renovated in such manner as to restore them substantially to their original state and condition as before use, so that prints made therefrom will 25 be clean, clear and perfect, eliminating the effects of "off feet" conditions incidental to the use of dirty type, as will be readily understood by those conversant, practically, with the art of typography, and thus obvi- 30 ating the former necessity for discarding old type fonts, and their replacement by new

fonts, an expensive expedient as compared with my system of type renovation.

It is to be understood that by the term "reticulated" as herein used, I mean to include intersticed or foraminulous structures of any kind adapted to admit of the passage of liquid therethrough, although in the present instance they are shown as of wire mesh.

An important incidental advantage of my 40 process of renovation is that the type is thereby restored to its original sanitary condition, so that its manipulation may be effected without danger to the compositor.

It is to be understood that the type pockets 45 t , may be made other than angular in shape with like results if so desired.

What I claim as my invention and desire to secure by Letters Patent, is:—

Type cleaning apparatus of the character 50 designated, comprising a wash-tray formed with a series of reticulated type pockets coincident in number and arrangement with the individual type box compartments of a compositor's type case, a reticulated cover for 55 said wash-tray, and means for detachably securing said cover to said wash-tray, the latter being formed with trunnions for the purpose and substantially in the manner set forth.

ISIDORE HIRSCH.
